REGULATION OF TELEVISION RECEIVERS

Kurt Schlesinger, Berlin, Germany, assignor, by
mesne assignments, to Loewe Radio, Inc., a cor-
poration of New York

Application December 9, 1935, Serial No. 53,534
In Germany December 10, 1934

5 Claims. (Cl. 178—7.5)

The invention relates to a method and an arrangement in which potentials for automatic regulation of the degree of amplification of television receivers are employed.

5 The subject matter of the present invention is a special performance of this method and a special device which improves the known arrangement for performing this method.

The reception of television transmissions provides a special problem in the question of regulation of the sensitivity of reception, which problem differs from those usual in the radio art and accordingly calls for novel methods of solution. In a high-class television receiving system the 10 light intensity of the television tube should be in direct proportion to the strength of the field at the place of reception, independently of the frequency with which this strength of field is modulated. If, therefore, the transmitter provides a constant strength of field, and if, as is necessary in the case of present-day receiving apparatus, the D. C. component is transmitted to the television tube, the light intensity of the image would fluctuate up and down upon varying the receiving amplification by means of a control knob, because the high frequency reaching the rectifier would be large or small dependent on the amplification, and it is a condition that the light intensity of the television tube be 15 proportional to the excitation. Since on the other hand the light intensity value in the case of unmodulated carrier wave should correspond with the "black" value of the images, a dependency of this kind is not permissible. The mean 20 value of the light intensity would be displaced more and more towards white if the amplification factor were increased, say, for the purpose of obtaining greater image potentials. A second control knob would then be necessary for adjusting the mean light intensity of the television tube, which knob would require to be actuated in reverse direction dependent on the adjustment of the receiving amplifier. A complicated and positive adjustment of this kind in 25 reception is not to be expected of the unskilled user. The problem accordingly arises of regulating the amplification factor of the receiving amplifier automatically, and raising the same to that level, or maintaining it constant at that 30 level, at which the image contents potential picked up upon full modulation of the transmitter fully modulates correctly the television tube. In similar cases in the radio art there is employed a special rectifier which rectifies the 35 carrier wave, and the rectified potential of which

biasses the amplifier. This method is fundamentally incapable of use for television purposes. If for example there is considered a television transmitter, which radiates powerfully upon "white" and weakly upon "black", and if there 5 is imagined a scene taking place continuously in black, i. e., with poor lighting, a regulating rectifier coupled with the carrier wave amplification would supply to the amplifier during the scene too small a controlling potential and would accordingly cause the amplifier to perform a higher amplification. In view of the previous remarks this would result in turn in the fact that the medium light intensity of the image would be increased, and the correct mean value, viz., 10 black, would be displaced towards white. Vice versa, very white images, for example upon the transmission of snow scenes, regulated according to the method known in the radio art, would necessarily prove to be too black. 15

20 It is one idea of the present invention to derive the amplifier regulating potential not from the carrier frequency, but from the synchronisation signals occurring after the rectifier of the receiver. The second idea in the invention consists in not rectifying these synchronisation signals by the amplitude filter which is present in any case, but to employ this amplitude filter solely for the synchronisation and to use a special regulating rectifier, which converts the synchronisation peaks into direct potential independently of the amplitude filter. The third idea in the invention consists in not transmitting the synchronisation peaks to this regulating rectifier directly, as would be necessary and convenient 25 in the case of the amplitude filter, but capacitatively or inductively, as in this way it is accomplished that the excitation of the regulating rectifier rises and falls together with the strength of field in the receiver, whereas in the case of direct connection the excitation of the amplitude filter remains independent of the strength of the receiving field. This capacitative or inductive coupling is preferably tuned to the synchronisation signal frequency. 30

35 The conditions will be explained in conjunction with the single figure of the drawing. An aerial 1 is coupled with the carrier wave amplifier 2, which is also coupled with the local oscillator 3, so that an amplified carrier frequency occurs at 40 the output transformer 4. This frequency is rectified in the grid current rectifier arrangement 5 for ultra-short waves described in previous specifications, and converted without any traces of carrier frequency into a video frequency, 45 50 55

which occurs at the resistance 6 and is passed direct to the television tube 8 by way of a lead 7. The only factor which in the case of each transmission remains constant independently of the contents of the image is the fact that the carrier wave is caused to disappear during the synchronisation impulses. The absolute height of this impulse represents, therefore, independently of the contents of the image, an exact measure as regards the strength of the receiving field with a given amplification factor in 2. As well known, the transmitter is adjusted to a certain average aerial feed current, for example to 30% of its maximum aerial current. The amplitude filter 9 is connected directly by its cathode with the lead 7 through the medium of the line 10. In this way, as explained earlier, it is accomplished that at the transformer 11 there is obtained a positive impulse potential, which may be conducted to the relaxation apparatus of the receiver, and the amount of which may be regulated once and for all by the counter-potential 12. When the amplification of the receiving amplifier 2 is increased, or the strength of field becomes greater, the impulse potential allowed to pass through the filter tube 9 in no way varies, because the potential 12 is so adjusted that a current is able to traverse 9 only when the carrier wave ceases. As the strength of signal increases the cathode potential 10 recedes more and more from the break-down potential of the tube 9, and all signalling amplitudes increasing in this direction serve to block the tube better. In consequence the filter tube 9 serves only the highest peaks from the impulses, and is not affected in its output circuit 11 by any variation in the strength of reception. This is of great advantage for the operation of the television receiver, and prevents the very undesirable overloading effects on the scanning apparatus. According to the invention, therefore, the amplitude filter 9 is entirely separated from the circuits which act by varying the bias on the receiving amplifier, and has no other object to fulfill beyond that described.

According to the invention, there is employed for the regulating function a new and second rectifier 13. This in accordance with the invention is coupled with the output lead 7, i. e., with the rectified received potential, only by way of alternating current circuit, and not directly, for example by means of a condenser 14. As regulating rectifier 13 there is shown in the drawing a crystal detector, the direction of the arrow indicating its transmission. The use of simple rectifiers of this nature, which are desirable for economic reasons and in view of the simple function of 13, is only rendered possible if, by means of a series resistance 15 of approximately ten times the size of 6, the capacitative shunts represented by the capacities of the rectifier 13 are prevented from affecting the image lead 7. By means of a resistance 16, which in turn requires to be large in relation to 15, a manually adjustable bias 17 is supplied to the cathode of 13. There is thus produced a delayed initiation of the regulation, and in this way the maximum amplification which may be maintained automatically by the receiver is determined once and for all. The bias 17 is preferably adjusted once at the back of the apparatus and then not further altered. The condenser 18 is so selected as regards its capacity that it is capable of following potential variations at the desired rate of several images. The regulating potential re-

sulting at the same is then supplied to the amplifying valves of the intermediate-frequency amplifier 2. In practice the orders of magnitude in the case of 180-line images are as follows:

Audion resistance 6=5000 ohms.

Protective resistance 15=50000 ohms.

Leakage resistance 16=0.5 megohm.

Leakage resistance 19=0.5 megohm.

Blocking condenser 18=approx. 0.5 mf.

The leakage resistance 19 has the object of providing for a sinking of the bias with which the condenser 18 is charged when the reception decreases. The time constant of the circuit 18/19 is selected in the manner known per se dependent on the requirements placed on the rate of regulation.

As regards the practical embodiment, it may be remarked that the contact rectifier 13 may also be replaced by other valves. The use of contact rectifiers merely offers economical advantages and no disadvantages of any kind. In the case of hot-cathode rectifiers of small dimensions 15 may possibly be omitted. The amplitude filter 9 is united in practice with the detector valve 5 in one glass bulb, as described in the application Ser. No. 45,729/35.

I claim:

1. A television system for receiving a carrier wave modulated with picture signals and synchronizing impulses, comprising a receiver having an input, a plurality of amplifying tubes and an output, a demodulating device for producing detected picture signals and synchronizing impulses, an amplitude filtering device for separating the synchronizing impulses from the picture signals, a rectifier including a cathode and an anode, means including a condenser for applying the detected picture signals and synchronizing impulses between the cathode of said rectifier and a point of fixed potential, a source of potential and an impedance for normally maintaining the cathode at a predetermined potential relative to the point of fixed potential, a time constant circuit including a parallel connected resistance and condenser connected between the anode of the rectifier and the point of fixed potential, and means for altering the effectiveness of at least one of the amplifying tubes in accordance with the potential present at the anode of the rectifier.

2. A television system for receiving a carrier wave modulated with picture signals and synchronizing impulses and wherein the synchronizing impulses have a greater amplitude than the picture signals, comprising a receiver having an input, a plurality of amplifying tubes each having a control electrode, and an output, a demodulating device for producing detected picture signals and synchronizing impulses, an asymmetric unit including a cathode and an anode, means including a condenser for applying the detected picture signals and synchronizing impulses between the cathode of said asymmetric unit and a point of fixed potential, a source of potential and a high resistance for normally maintaining the cathode at a predetermined substantially constant potential relative to the point of fixed potential, a time constant circuit including a parallel connected resistance and condenser connected between the anode of the asymmetric unit and the point of fixed potential, and means for connecting the control electrode of at least one of the amplifying tubes to the anode of the asymmetric unit to alter the effectiveness of

the amplifying tube in accordance with changes in the potential at the anode of the asymmetric unit.

3. A television system for receiving a carrier wave amplitude modulated with picture signals and synchronizing impulses and wherein the synchronizing impulses have a greater amplitude in a predetermined direction than the picture signals, comprising a receiver having a plurality of amplifying tubes each including a control electrode, a demodulating device for producing detected picture signals and synchronizing impulses, an amplitude filtering device for separating the synchronizing impulses from the picture signals, a diode rectifier including a cathode and an anode, means including a condenser and a series resistance for applying the detected picture signals and synchronizing impulses between the cathode of said diode and a point of fixed potential, a source of potential and a resistance for normally maintaining the cathode at a potential difference relative to the point of fixed potential, a time constant circuit including a parallel connected resistance and condenser connected between the anode of the diode and the point of fixed potential, and means for connecting the control electrode of at least one of the amplifying tubes to the anode of the diode to alter the effectiveness of the amplifying tube

in accordance with changes in the charge on the condenser of the time constant circuit associated with the anode of the diode.

4. In a television system in which the synchronizing impulses have a higher amplitude than the video signals means for fading regulation of a television receiver by varying the bias of at least one of its high frequency amplifiers, said means consisting of a biased rectifier coupled inductively to the control electrode of the cathode ray tube of said receiver so as to charge a storage condenser being provided with a leakage resistance and being connected to a grid of said amplifier, said inductive coupling being tuned to the synchronizing frequencies. 15

5. In a television system in which the synchronizing impulses have a higher amplitude than the video signals means for fading regulation of a television receiver by varying the bias of at least one of its high frequency amplifiers, said means consisting of a biased rectifier coupled to the control electrode of the cathode ray tube of said receiver so as to charge a storage condenser being provided with a leakage resistance and being connected to a grid of said amplifier, 20 25 said rectifier consisting of a crystal detector of very low capacity.
